MECHANISM AND PROCESS FOR EFFECTING REVERSE PLATING BY NEEDLE DEFLECTION

John Lawson and Robert H. Lawson, Pawtucket, R. I., assignors to Hemphill Company, Central Falls, R. I., a corporation of Massachusetts

Application May 26, 1927, Serial No. 194,504

3 Claims. (Cl. 66—36)

This application is a continuation as to common subject-matter of the co-pending application Serial No. 145,512, filed November 1, 1926, now Patent No. 1,897,130 wherein it was stated that while the jacks are shown and described as moving special instrumentalities so as to result in reversing the position of the back and face yarns, the said jacks might be employed to give suitable in or out movement, or both, to certain needles instead of to special instrumentalities, and thus result in reversing the position of the back and the face yarns, thereby securing reverse plating.

In order that the principle of the invention may be readily understood, we have disclosed two embodiments thereof in the accompanying drawings, wherein—

Fig. 1 is a plan view of the web holder bed ring and certain related parts;

Fig. 2 is a horizontal section taken through the two dial disks of a so-called diagonal striper reverse plating machine and through the sinker or web holder bed ring and showing certain of the web holders in position therein;

Fig. 3 is a detail in plan of the construction shown in Fig. 4;

Fig. 4 is a vertical section taken through a part of the needle cylinder, the sinker or web holder bed ring and the cap ring, and showing certain instrumentalities or special jacks in non-functioning position, that is, as not deflecting the needles;

Fig. 5 is a detail in plan of the structure shown in Fig. 6;

Fig. 6 is a vertical section similar to Fig. 4 but representing an instrumentality or special jack as deflecting its needle;

Fig. 7 is a vertical transverse section similar to Fig. 4 but representing the means for driving the dial disks or members carrying the instrumentalities or special jacks;

Fig. 8 is a horizontal section of another embodiment of the invention, being taken through the needle cylinder, a dial disk and a jacquard or patterning drum by which jacks of the dial disk are selected for action upon the special instrumentalities of the knitting head;

Fig. 9 is a view in vertical transverse section taken through the needle cylinder, the sinker or web holder bed ring and the cap ring and representing a special instrumentality or jack, as in non-functioning position with respect to its needle;

Fig. 10 is a view similar to Fig. 9, but repre-

senting the instrumentality or special jack in functioning position with respect to its needle; and

Fig. 11 is a side elevation of parts shown in Fig. 8.

In our application hereinbefore referred to, we have disclosed means whereby the jacks move special instrumentalities in the nature of thread-engaging web holders or sinkers, whereby reverse plating is effected. In the present application we disclose means whereby a similar construction is employed for the purpose of deflecting needles to which yarns are fed in a plating relation, so as to secure reverse plating as a result of such needle deflection.

Referring first to that form of the invention disclosed in Figs. 1 to 7 inclusive and making reference for full disclosure of the general mechanism of the machine to the said parent application Serial No. 145,512, it is pointed out that in the practice of the present invention, there is employed a series of independent needles desirably arranged in a circular knitting machine. A needle cylinder 1, which may be of the Banner or Hemphill type, is herein shown as provided with needles 2, which desirably are latch needles, but which may be of any suitable type. The sinker or web holder bed ring is represented at 3, and it is provided with usual grooves 4, which, however, may if necessary be of greater width than where a single instrumentality is employed in these grooves.

In each of said grooves there is inserted for in and out or radial movement a web holder 5 desirably of usual type and which may be of the form shown in Figs. 4 and 6. Said web holders are provided with butts 6 received in an inner groove 7 of the cap ring 8. The said web holders function in the usual manner. In addition there is positioned in each of the grooves 4 an instrumentality or special jack 9 having at its outer end a butt 10 which may be positioned either in a groove 11 in the cap ring, which groove constitutes an inner or working pathway, or may be positioned in an outer groove or path 12, which constitutes the non-working groove or pathway. Each of the said instrumentalities or special jacks 9 is provided with an inner head or bent or specially shaped inner end 13 adapted at designated or predetermined times to engage its needle 2 at or near its upper end or desirably below the pivot of the latch, so as to deflect the same inward sufficiently to produce reverse plating.

It is to be understood that two yarns are fed

to the needles in a plating relation, as for example, in the manner disclosed in the patent to Robert H. Lawson, No. 1,605,895, or in the re-issue patent to Robert H. Lawson, No. 16,584. 5 The yarns being fed in a plating relation to the needles and the instrumentalities or special jacks 9 being in their non-functioning position, normal plating results whether one of the yarns be fed under greater tension than the other as disclosed in the said reissue patent, or whether there 10 be no particular provision for imparting greater tension to one yarn than the other. Where, however, needles are inwardly deflected to a slight extent as, for example, about one thirty- 15 second of an inch at the upper end, reverse plating results.

In order to deflect desired needles by means of the instrumentalities or special jacks 9, we provide pattern means by which the desired instrumentalities or special jacks 9 are moved into or caused to be positioned with their butts in the working groove or pathway 11 instead of in the outer or non-working pathway 12. The pattern means may be and desirably is of the general 20 type shown in the said application 145,512. It is of such type as will permit any or every needle to have reverse plating effected thereon, depending, however, upon the arrangement of certain stationary jacks to be described. Desirably 25 there is employed a part or parts rotating with the rotating part of the knitting organization. Assuming for purposes of description merely that the needle cylinder is to be rotated, it is evident that such rotation may be effected in any suitable 30 manner. It is preferable to provide teeth either upon the sinker or web holder cam ring or upon the needle cylinder, and herein are represented teeth 14 upon a ring 15 secured as by screws 16 upon the sinker or web holder cam ring (see 35 Figs. 4 and 6) extending entirely about the same. Meshing therewith there are in the present instance provided two toothed disks or gears, one of which is shown at 17, fast for rotating movement upon a spindle 18 received in suitable 40 bearings in a manner more fully disclosed in said parent application, the number of teeth desirably being either the same as the number of needles in the machine, or bearing some fixed ratio thereto. As shown in Fig. 7, on the spindle 18 there 45 is fast a collar 19 by means of the set screw 20, and the toothed disk 17 is provided with a hub or sleeve-like portion 21 by which said toothed disk is secured to the spindle 18 by set screw 22. Desirably the two toothed disks or gears (if both 50 are employed) are of similar construction and in Fig. 2 the relative position thereof is indicated, the spindle of the other disk being indicated at 55 18'. There are provided, as disclosed in said parent application, the two pattern disks 23, 24, 60 with grooves 25, 26 in the upper face of an outer annular portion of the disks as clearly shown in Fig. 7 for the ready reception therein and ready removal therefrom of a series of jacks. Desirably the jacks are inclined with 65 respect to the centers of the disk as stated in said parent application. Within the said grooves 25, 26, or such of them as are required for the production of the particular pattern that is to be 70 produced, there are inserted jacks 27, which in this form of the invention do not reciprocate in the said grooves, but are held in position therein by the overlying rims or annuli 28, 29, as indicated most clearly in Figs. 2 and 7. The said jacks 27 are desirably of the form shown in said parent application and need not be more particularly 75

described otherwise than to state that they are provided with heads or bent ends 30, which may be and desirably are of the form shown in said application previously referred to. The said heads or bent ends 30 instead of acting upon 5 special instrumentalities which themselves engage one or both threads in effecting change from normal to reverse plating, act upon the special instrumentalities or jacks 9 that cause needle deflection as already stated. It is to be understood that in this form of the invention jacks 21 10 may be positioned wherever desired in either or both of the disks or within the scope of the invention they may be otherwise supported for the purpose of acting upon instrumentalities or 15 special jacks that cause needle deflection. The arrangement shown in Fig. 2 is for purpose of description or disclosure merely.

Referring to Figs. 1 and 2, it is to be understood that where no jacks or elements 27 are 20 employed, the instrumentalities or special jacks 9 are left in their outer or non-functioning position, namely, with their butts in the outer groove or pathway 12. Where, however, a jack 27 is employed to engage a corresponding instrumentalities or special jack 9 the head 30 thereof engages the butt 10 as indicated in Fig. 2, and moves the same inward so that said butts are received in the groove or pathway 11 which is the working or functioning groove or pathway, as 30 already stated.

Referring to Fig. 1, it will be observed that the wall or formation 31 between the pathways 11 and 12 is of suitable cam shape so as to cause the instrumentalities or special jacks 9 which have 35 been so moved that their butts 10 are received in the groove or pathway 11, to be pushed into the needle deflecting position shown in Fig. 6. For this purpose the said wall 31 is provided with an inwardly sloping formation 32 in proper relation to the knitting point so that as the needles approach the knitting point they are held deflected inwardly to a slight extent with the result that reverse plating results.

In Figs. 8 to 11 a second form of the invention 45 is disclosed, which differs from that shown in Figs. 1 to 7, in that the jacks which act upon the instrumentalities or special jacks employed to deflect the needles, are themselves adapted for lengthwise movement and are so moved by a selecting device.

In Fig. 8, one form of selecting device is indicated at 33 as consisting of a drum, cylinder or like member in the nature of a jacquard member and carried or supported by a shaft 34 so as to turn desirably in the direction of the arrow in Fig. 8. The surface of the drum 33 is provided with suitable projections 35 wherever desired, and which may be of the general form and construction shown in co-pending application Serial 60 No. 182,060 now Patent No. 1,872,598. The said projections 35 wherever employed engage the heads or bent outer ends 36 of jacks 37 which are mounted for sliding movement in grooves 38 which may be radial or nearly radial as already 65 disclosed with respect to the first form of this invention.

The grooves 38 within which the jacks 37 are received are provided in a suitable disk member generally indicated at 39' in Fig. 11, and which 70 is supported for rotation upon a suitable spindle 39 which has a toothed disk 40 meshing with a toothed ring or gear 41 fast upon the sinker cam ring or other suitable part of the knitting head. Also the spindle 39 may have fast thereon a 75

gear 42 which meshes with and drives the gear 43 fast with or upon the shaft 34 so as to rotate the same in unison with the knitting head and the disk 38.

5 The jacks 37 are provided with butts 44 which may be positioned either in the working or functioning groove 45 shown in Fig. 8 or in the non-working or non-functioning groove 46. The pins or projections 35, if present, engage the heads 10 36 of jacks 37 and push said jacks inward as indicated at 47 so that their butts 44 are located in the non-working groove 46. Thus the absence of projections 35 means that the corresponding jacks 37 are left with their butts 44 in the outer 15 or working groove 45 and being left in such position they in turn act upon the instrumentalities or special jacks 48 shown in Figs. 9 and 10, and which engage the shanks of the needles 2 as already described with respect to Figs. 1 to 7, it being understood that the stems of all the needles in both forms of the invention are slightly bent as indicated at 2' so that the needle stems may be readily deflected in effecting reverse plating.

Substantially in or directly above the working 25 groove or pathway 45 is positioned a cam 49 which is movable up or down by suitable automatic connections and which when down, as for heel and toe work, causes all the jacks 37 to move into the non-working groove 46. The non-working groove 46 is preferably provided with a cam formation 50 by which all the jacks 37 are moved outwardly, so that they may be reselected 30 for the next rotation of the knitting head. As shown most clearly at 51 in Fig. 8, the wall 52 between the grooves 45, 46 is suitably formed so as to hold a number of the jacks 37 in deflecting 35 engagement with the needles 2 at or in vicinity to the knitting point which is substantially at 51. The number of jacks so held in deflecting engagement with the needles at this location is shown as five, but it may be more or less as found 40 desirable. It will be understood that in the form of the invention shown in Figs. 8 to 11, the instrumentalities or special jacks 48 may be located 45 at the proper position or height lengthwise the needle cylinder to cause needle deflection in the proper manner for effecting reverse plating.

In this form of the invention regular web 50 holders or sinkers, such as 5, are employed, as described with respect to the first form of the invention, but they are located each in a separate groove and without any needle deflecting 55 instrumentality in the same groove; that is to say, in the form of our invention shown in Figs. 1 to 7 the needle deflecting instrumentalities or special jacks are located in the sinker or web holder grooves whereas in that form of the invention shown in Figs. 8 to 11 the instrumentalities or special jacks which cause needle deflection are 60 located in grooves or formations other than the sinker or web holder grooves, and for this purpose they are desirably located as shown in Figs. 9 and 10, beneath the web holder bed ring 3. It

will be observed that in this form of the invention the walls of the needle grooves are cut away slightly as indicated at 54 in Figs. 9 and 10 so as to permit the instrumentalities or special jacks 48 to engage the shanks of the needles 2 by their 5 heads and properly to deflect the same.

Having thus described certain embodiments of mechanism for practicing our invention and the best mode known to us for carrying out the method of our invention, we desire it to be understood that although specific terms are employed, they are used in a generic and descriptive sense and not for purposes of limitation, the scope of the invention being set forth in the following claims.

We claim:—

1. In a circular knitting machine, a circular series of independent needles to which two threads are adapted to be fed in a plating relation, slotted supports, web holders operable between said needles and sliding in slots in said support, jacks each associated respectively with a web holder and slidably parallel to said web holders in slots in said support and adapted to engage the needle shanks to deflect the same at 25 their loop forming ends, and means on the hook side of the needles for causing said jacks to deflect predetermined needle shanks sufficiently to cause a change in the plating relation of the two threads with continued feeding of both threads 30 to the selectively deflected needles and pattern means for acting upon said jacks.

2. In a knitting machine, a series of independent needles to which two threads are adapted to be fed in a plating relation, slotted supports, web 35 holders operable between said needles and sliding in slots in said support, jacks each associated respectively with a web holder and slidably parallel to said web holders in slots in said support and adapted to engage the needle shanks to deflect 40 the same at their loop forming ends, and means on the hook side of the needles for causing said jacks to deflect predetermined needle shanks sufficiently to cause a change in the plating relation of the two threads with continued feeding 45 of both threads to the selectively deflected needles and pattern means for acting upon said jacks.

3. An independent needle knitting machine having needles independently mounted therein, 50 in combination with jacks adapted to be selectively controlled during the knitting of courses, and means adapted, first selectively to divide the jacks into an active set and an inactive set, said means thereafter being adapted to move the active set of jacks in the direction of their length 55 which movement is at right angles to the length of the needles whereby the jacks modify the movements of the needles and thereby cause variations in the knitted fabric.

JOHN LAWSON.
ROBERT H. LAWSON.
